UNITED STATES PATENT OFFICE.

LOUIS LEBOVITZ, OF PITTSBURGH, PENNSYLVANIA.

DESIGN FOR A GAS-STOVE.

43,504.

Specification for Design.

Patented Feb. 4, 1913.

Application filed December 13, 1912. Serial No. 736,622. Term of patent 14 years.

To all whom it may concern:

Be it known that I, LOUIS LEBOVITZ, a citizen of the United States, and a resident of Pittsburgh, in the county of Allegheny and State of Pennsylvania, have invented a new, original, and ornamental Design for Gas-Stoves, of which the following is a specification, reference being had to the accompanying drawing, forming a part thereof.

The drawing is a perspective view of a gas stove showing my new design.

I claim:

The ornamental design for a gas stove, as shown.

LOUIS LEBOVITZ.
